UNITED STATES PATENT OFFICE.

PETER KELLER, OF CHICAGO, ILLINOIS.

GAS-REGULATOR.

1,078,625.

Specification of Letters Patent. Patented Nov. 18, 1913.

Application filed May 16, 1912. Serial No. 697,625.

To all whom it may concern:

Be it known that I, PETER KELLER, a citizen of the United States, residing at the city of Chicago, in the county of Cook and State of Illinois, have invented a new and useful Improvement in Gas-Regulators, of which the following is a specification.

My invention relates to devices for regulating the flow of illuminating gas.

10 The object thereof is to provide a simple, cheap and effective check or regulator for use in connection with gas burners of any kind, whereby the pressure of gas in the service pipe may be modified so that when 15 delivered at the burner tip the gas pressure is uniform and lowered to the point of economical and effective consumption.

The principles of my invention are illustrated in the drawings, in which—

20 Figures 1 and 2 show sectional views of my improved regulator, having different styles of burners mounted thereon; Fig. 3 is an enlarged vertical section shown in perspective; Fig. 4 is a cross section of Fig. 3 25 on the line 4—4; Fig. 5 is a slightly modified form of the device.

Further describing my invention with reference to the drawings, in which like characters of reference denote like parts throughout: 1 and 1' represent the pillars of different types of gas burners, provided with non-fusible tips and having their lower portions screw-threaded for attachment to an ordinary gas bracket.

35 2 represents the casing of my improved regulating device, having the upper ends above the shoulder 3 threaded with standard bracket threads so as to enter the lower part of the pillar, and having the lower portion 40 threaded to receive the thread of a gas bracket. The upper end or dome 4 of said casing has a central aperture 5 and should be lined on its underside by a wire screen 6, pressed snugly in place thereagainst. This 45 is not, however, necessary and the screens may be of very coarse mesh. A partition piece 7 provided with a multiplicity of regularly disposed openings is placed within the said dome and spaced therefrom, leaving a 50 chamber through which the gas passes. Said chamber forms a receptacle which is filled with finely cut steel or other metallic shavings. These act as a check for the gas passing through it as further described below.

55 A construction alternative to that just described is illustrated in Fig. 5 in which the

perforated partition piece is replaced by a disk 7' of wire cloth or screen. The inside of said casing is further provided with a shoulder 10. A shell of brass or other metal having a body portion 11 and a depending flange 12 is placed within the casing in such position that the said shell fits closely against and is positioned by said shoulder. The head of said shell is provided with an opening 13. In the chamber between said shell and the partition 7 is placed a cup-shaped float or valve of brass or other suitable material having downwardly depending walls 15 and a flat top 16. A depression 17 is formed in said top thereby creating a correspondingly downwardly projecting member within the cup which will normally rest transversely of the shell 11 and partially close the opening 13. This will be the normal position under the influence of gravity when the gas is not turned on. As soon as the flow begins upwardly through the opening 13 the float will be lifted, permitting the gas to flow out of opening 13 into the float 20 and thence around the walls 15 and upwardly through the openings 8; but any excess of gas pressure above that required for economical consumption will raise the float until the portion 16 is in contact with the partition 7, whereby the openings 8 will be obstructed, except where they are coincident with the depression 17. A uniform resistance or check is provided in the space or chamber between screen 6 and partition 7. 25 This I pack with finely cut shavings of steel or other elastic metal, though I prefer the former as I have found it to be peculiarly fitted for this purpose. Being cut from solid steel and by a process which curls the shavings or fibers, the said material is highly elastic and capable by greater or less compression of giving such definite resistance to the gas current as desired. This elasticity is not lost nor is the material otherwise deteriorated by age or by the extreme heat to which it is subjected and by which all other materials, usually fibrous and of organic origin when similarly used, are injured or destroyed. And when placed in 30 proper quantity between the dome of my device and the foraminous partition 7 or 7' it forms a fixed and definite check against too rapid flow of gas. It coöperates most efficiently with the valve 16, and I thereby obtain a continuous, uniform low pressure flow of gas and produce a soft, clear and brilliant 35

light at a less cost than when gas is burned under ordinary conditions.

I claim:

1. In a gas check, a casing, an upwardly tapered shell having an opening in the apex thereof within the said casing, a foraminous partition placed transversely within said casing above said shell to form a valve chamber and an inverted cup-shaped float in said 10 chamber placed over said shell and having a flat top with an internal depending member to ride on the apex of said shell and close said opening.
2. In a gas check, a casing, an upwardly tapered shell having an opening in the apex thereof within the said casing, a foraminous partition placed transversely within said casing to form a valve chamber and an inverted cup-shaped float in said chamber 20 placed over said shell and having a depression in the top forming an internal depending member to ride on the apex of said shell and close said opening.

3. In a gas pressure regulator; the combination with a hollow casing, having an outlet opening in the head of a transverse foraminous partition forming a retaining chamber below said head, a packing for said chamber of steel or other metallic shavings, an upwardly tapered shell having an opening in the apex thereof secured in the lower part of said casing to form a valve chamber below said partition, and an inverted cup-shaped float placed over said shell and having a substantially flat top and an internally depending member to ride on the apex of said tapered shell and obstruct the opening thereof.

In witness whereof, I have hereunto subscribed my name in the presence of two subscribing witnesses, this fourteenth day of May A. D. 1912.

PETER KELLER.
